UNITED STATES PATENT OFFICE.

CARL JOHAN HOFFMAN, OF DENVER, COLORADO.

RAIL-JOINT.

SPECIFICATION forming part of Letters Patent No. 760,864, dated May 24, 1904.

Application filed November 21, 1903. Serial No. 182,143. (No model.)

To all whom it may concern:

Be it known that I, CARL JOHAN HOFFMAN, a citizen of the United States, residing at Denver, in the county of Denver and State of Colorado, have invented new and useful Improvements in Rail-Joints, of which the following is a specification.

My invention relates to new and useful improvements in rail-joints; and its object is to provide a rail having the ends thereof shaped in a novel manner, whereby the adjoining ends of two of such rails can be securely fastened together, so as to prevent sagging and form a strong and durable joint.

The invention consists in providing a tongue at each end of the rail, said tongues being located at opposite sides of the ends of a rail-web and one of them having base-flanges which are similar to the base-flanges of the body of the rail, one of said base-flanges being provided with a longitudinally-extending groove in its face, which alines with the exposed portion of the end of the web of the rail. The tongue at the other end of the rail has a head which is similar to and integral with the head of the body of the rail, and a groove is formed within the inner face of this head in alinement with the exposed portion of the adjoining end of the web of the rail. The rails are adapted to be assembled by overlapping the tongues thereof, so as to permit the head of one tongue to receive the upper edge of the other tongue, while the grooved base-flange of said last-mentioned tongue receives the lower edge of the headed tongue. Bolts are employed for securing the tongues together, and fish-plates may also be provided where the tongues abut against the webs of the rails.

The invention also consists in the further novel construction and combination of parts hereinafter more fully described and claimed, and illustrated in the accompanying drawings, showing the preferred form of my invention, and in which—

Figure 1 is a side elevation of a rail constructed in accordance with my invention, the central portion of said rail being removed. Fig. 2 is a side elevation of the joined ends of

two rails, and Fig. 3 is a section on line 3 3, 50 Fig. 2.

Referring to the figures by numerals of reference, 1 is the web of a rail having base-flanges 2 at the lower edge thereof and a head 3 at the upper edge. A tongue 4 extends longitudinally from one end of the web, said tongue being one-half the thickness of the web and having its outer face in alinement with the corresponding face of the web. Base-flanges 5 and 6 extend from this tongue 4, and arranged upon the base-flange 6 is a longitudinally-extending groove 7, the bottom of which is concaved in cross-section, and this groove alines with the exposed adjoining end of the web 1 and is equal in width to the width of 65 said exposed portion. A tongue projects from the other end of the web 1 and is equal in thickness to one-half of the thickness of said web, and the outer face of this tongue is in alinement with the adjoining face of the web. 70 The lower edge of tongue 8 projects a short distance below the lower edge of the web 1 and is convexed in cross-section. A head 9 is formed upon tongue 8 and integral with the head 3, and this head has a longitudinally-extending groove 10 in its lower face, which is in alinement with the exposed portion of the adjoining end of web 1 and is concaved in 75 cross-section. Apertures 11 are formed within the tongues 4 and 8 and in the ends of the 80 web 1.

To assemble the rails, the tongues 4 and 8 are caused to overlap, the convexed lower edge of the tongue 8 being placed within the concaved groove 7, while the groove 10 receives the upper edge of the tongue 4, said tongue being rounded to conform to the contour of the wall of the groove 10. It will be understood that the tongues 4 and 8 will abut against the adjoining ends of the webs 1, and 90 when in such position the apertures 11 will register and permit the insertion therethrough of bolts 12. A fish-plate 13 is removably secured over the ends of the tongues and the adjoining ends of the webs 1, and these fish-plates fit snugly with their edges upon the base-flanges 2 and 5 and the heads 3 and 9. It will be seen that the ends of rails con-

structed in this manner cannot be separated after they have been assembled except by first raising them, so as to lift the heads 9 from the tongues 4 and the tongues 8 from 5 the flanges 6. The adjoining ends of the rails are firmly supported, and therefore pounding by car-wheels passing thereover is prevented and a smooth joint produced.

In the foregoing description I have shown

- 10 the preferred form of my invention; but I do not limit myself thereto, as I am aware that modifications may be made therein without departing from the spirit or sacrificing any of the advantages thereof, and I there- 15 fore reserve the right to make such changes as fairly fall within the scope of my invention.

Having thus described the invention, what is claimed as new is—

- 1. A rail having tongues extending from 20 opposite sides of the ends of the web thereof, a head integral with one of the tongues and alining with the head of the rail, said head of the tongue having a longitudinally-extending groove in its lower face alining with the ex- 25 posed adjoining end of the web, base-flanges extending from the bottom of the other tongue and alining with the base-flanges of the rail, one of said flanges of the tongue having a lon- 30 gitudinally-extending groove therein alining with the exposed portion of the adjoining end of the web.
- 2. A rail having tongues extending from the ends of the web thereof, said tongues being arranged at opposite sides of the ends of 35 the web, a head integral with one of the tongues and alining with the head of the rail, said head having a longitudinally-extending groove in the lower face thereof alining with the ex- posed portion of the adjoining end of the web,

base-flanges extending from the other tongue 40 alining with the base-flanges of the rail, one of said base-flanges of the tongue having a longitudinally-extending groove therein alining with the exposed portion of the adjoining end of the web, said grooves being concaved 45 in cross-section to conform to the convexity of the upper and lower edges, respectively, of the tongues.

3. The combination with a rail having a tongue extending from one end thereof, said 50 tongue being of less thickness than the web and having a head thereon integral and alining with the head of the rail and having a longitudinally-extending groove in its lower face alining with the exposed portion of the 55 end of the web; of a rail having a tongue ex- tending from one end thereof and of less thick- ness than the thickness of the web, said tongue being adapted to overlap the first-mentioned tongue and having a rounded upper edge 60 adapted to be seated within the groove in the head, base-flanges upon the last-mentioned tongue, one of said flanges having a lon- 65 gitudinally-extending groove alining with the ex- posed portion of the adjoining end of the web and adapted to receive the lower rounded edge 70 of the tongue on the first-mentioned rail, fish- plates extending over the abutting ends of the tongues and rails, and bolts extending through the tongues and fish-plates and rails for secur- ing the parts together.

In testimony whereof I affix my signature in presence of two witnesses.

CARL JOHAN HOFFMAN.
